CLAIM

The ornamental design for a tablet case with pen slot, as shown and described.

DESCRIPTION

FIG. 1 is a front elevational view of the tablet case with pen slot showing my new design;
 FIG. 2 is a rear elevational view thereof;
 FIG. 3 is a left side elevational view thereof;
 FIG. 4 is a right side elevational view thereof;
 FIG. 5 is a top plan view thereof;
 FIG. 6 is a bottom plan view thereof;
 FIG. 7 is a front perspective view thereof;
 FIG. 8 is a front perspective view thereof, showing the tablet case in use position; and,
 FIG. 9 is a rear perspective view thereof.
